(57) CLAIM

The ornamental design for a mat for putting with perfect speed, as shown and described.

DESCRIPTION

FIG. 1 is a top plan view of a mat for putting with perfect speed embodying my new design;

FIG. 2 is a bottom plan view thereof;

FIG. 3 is left side view thereof, the right side view being a mirror image thereof; and,

FIG. 4 is a front view thereof, the rear end view being a mirror image thereof.
